C. A. ADAMS

IRONING BOARD AND SUPPORT

Filed Nov. 20, 1926

UNITED STATES PATENT OFFICE.

CLARA A. ADAMS, OF JACKSON, MICHIGAN.

IRONING BOARD AND SUPPORT.

Application filed November 20, 1926. Serial No. 149,625.

My invention relates to a new and useful improvement in an ironing board and the attachments of the ironing board for mounting it in its place of use.

5 The invention is intended to afford a means for mounting an ironing board permanently in any location, so as to occupy a minimum amount of space.

I am aware that a method of mounting 10 an ironing board permanently in a particular location has previously been produced, but these methods with which I am familiar are such that the ironing board occupies considerable space in the room in which mounted, and particularly in the wall into which the ironing board is moved when not in use.

The present invention has, as its object, 15 the mounting of the ironing board so that a minimum amount of space may be occupied, and so that the appearance of the room 20 may be altered but little.

Another object of the invention is the provision of a mounting of an ironing board of 25 this class in which the ironing board will swing in a horizontal plane from operative to inoperative position, and vice versa.

Another object of the invention is the provision of a mounting for an ironing board whereby the ironing board may be mounted 30 in a cabinet or other similar position in a room without altering the appearance of the room to the extent that the location of the ironing board could be noticed from observation.

35 Another object of the invention is the provision of a support for an ironing board which may be inserted into a small space and permanently fastened therein.

Another object of the invention is the provision of means for bracing the ironing board against swinging in either direction 40 when moved to operative position.

Other objects will appear hereinafter.

The invention consists in the combination 45 and arrangement of parts hereinafter described and claimed.

The invention will be best understood by 50 a reference to the accompanying drawings which form a part of this specification, and in which

Fig. 1 is a perspective view of the invention showing it mounted on a suitable support.

Fig. 2 is a sectional view taken on sub-

stantially line 2—2 of Fig. 3, showing the 55 ironing board enclosed in its receptacle.

Fig. 3 is a sectional view taken on substantially line 3—3 of Fig. 2.

Fig. 4 is a front elevational view of the invention showing the closure moved to open 60 position and the ironing board enclosed in the receptacle.

Fig. 5 is a fragmentary sectional view taken on substantially line 5—5 of Fig. 1.

In the drawings, I have illustrated the invention mounted in a cabinet or work table or cupboard 7, and in this connection it may be noted that the container for the ironing board may be mounted in any convenient location in the room, although when it is 65 mounted in the kitchen cabinets it may so form a part of the cabinets as to present an appearance in accordance with the other drawers and compartments of the cabinet.

Inserted into a space in the work table or 75 the cabinet is a box-like structure comprising a rear wall 8, end walls 9 and 10, a top wall 11 and a bottom wall 12. A front wall 13 is mounted on the receptacle, thus formed

and cut away as at 14 to provide a suitable 80 opening, this front wall 13 extending preferably beyond the edges of the end and top and bottom walls, to serve as a limiting flange.

A door 15 is suitably hinged upon the front wall 13 to serve as a closure for 85 the opening 14. An ironing board 16 is used which may be of conventional shape and type, and secured to the rear edge of

the ironing board is a block 17, through one 90 end of which is formed a passage in which is positioned a bushing or sleeve 18. Projected through the bushing or sleeve 18 is

a bolt 19 provided with the nut 20, thus 95 hingedly mounting the ironing board on the receptacle. In this connection it may be noted that the block 17 is of the same height

as the opening 14. Swingably mounted on the under surface of the ironing board is a cross bar 21 connected to which and projecting outwardly from which are legs 22 100 and 23, which are in turn connected at their lower ends by a base board 24. Mounted on the under surface of the board 16 is an abutment block 25 so arranged and constructed

that when the legs 22 and 23 are swung to 105 supporting position, as shown in Fig. 1, the cross bar 21 will engage on its face the face of the abutment block 25, this abutment block

25 thus serving to limit the swinging of the legs 22 and 23 in one direction. When the legs are moved to inoperative position they are located, as shown in Fig. 4, and I have provided a hook 26 which is screwed into the board 16 and adapted for moving into engaging position with the legs 23 to retain them in inoperative position, as shown in Fig. 4. When the board 16 is moved to operative position the closure 15 may be raised into engagement at its front edge with the under surface of said board 16, the inner surface of the closure, for a distance equal to the width of the board, being cut away as 15 at 27 to provide an abutment shoulder preventing the swinging of the board inwardly of said receptacle while said closure is in such engagement with said board. The hook 26 may then be turned to engage the closure 15, as shown in Fig. 5, thus retaining the board 16 in engagement with the shoulder and preventing a swinging of the board 16 in one direction. At the same time, as shown in Fig. 5, the block 17 engages the lower edge of the closure 15 so as to prevent a further swinging outwardly of the board 16 so that the block 17 is always retained within the receptacle formed in side walls described.

20 Attached to the block 25 is a flexible member, such as a chain 28, or the like, carrying the ring 29 which is adapted to engage a hook 30 carried on the inner surface of the closure 15 so that when the board 16 is moved into the receptacle, the ring 29 may engage the hook 30, and afford a means for drawing the board outwardly when the closure 15 is moved to open position.

25 In this manner, I have provided a receptacle for an ironing board, which serves as a supporting member and at the same time, as a receptacle for the ironing board when it is moved to inoperative position.

30 It is believed evident that the ironing board will be well concealed when not in use, and that the appearance of the room in which my invention is mounted will be altered but little from ordinary.

35 The particular mounting of the ironing board on the receptacle is, of course, illustrated as being the preferred form, but it is believed evident to those skilled in the art that other methods of attaching the board 16 swingably on the receptacle could be provided.

40 While I have illustrated and described the preferred form on construction, I do not wish to limit myself to the precise form of structure shown, but desire to avail myself of such variations and modifications as may come within the scope of the appended claims.

Having thus described my invention what I claim as new and desire to secure by Letters Patent is:

65 1. A device of the class described comprising a receptacle having an opening in one side thereof; a closure for said opening; an ironing board swingably mounted on said receptacle and adapted for swinging inwardly and outwardly of said receptacle through 70 said opening to an inoperative and an operative position respectively, said closure having a cut away portion to provide an abutment shoulder for engaging one edge of said board and preventing swinging of the same 75 inwardly of said receptacle.

80 2. A device of the class described comprising a receptacle having an opening in one side thereof; a closure for said opening; an ironing board swingably mounted on said receptacle and adapted for swinging inwardly and outwardly of said receptacle through said opening to an inoperative and an operative position respectively, said closure having a cut away portion to provide an abutment shoulder for engaging one edge of said board and preventing swinging of the same 85 inwardly of said receptacle; and means mounted on the inner end of said board engagable with said closure for limiting swinging movement of said board outwardly from said receptacle when the board is in operative position.

90 3. A device of the class described comprising a receptacle having an opening in one side thereof; a swingably mounted closure for said opening; an ironing board swingably mounted on said receptacle and adapted for swinging in a horizontal plane inwardly and outwardly of said receptacle through said opening; and an engagement block on said ironing board adapted for engaging said closure upon outward swinging of said ironing board from said receptacle 100 beyond a predetermined distance to prevent 105 farther outward swinging thereof.

4. A device of the class described comprising a receptacle having an opening in one side thereof; a swingably mounted closure for said opening; an ironing board swingably mounted on said receptacle and adapted for swinging in a horizontal plane inwardly of said receptacle through said opening; an engagement block on said ironing board adapted for engaging said closure and preventing outward swinging of said ironing board from said receptacle beyond a predetermined distance; and means for retaining said closure in position for engagement with said engagement block.

110 In testimony whereof I have signed the foregoing.

CLARA A. ADAMS.
